UNITED STATES PATENT OFFICE.

JAMES T. ROBERTS, OF ANDERSON, SOUTH CAROLINA.

FABRIC-TUFTING MACHINE.

SPECIFICATION forming part of Letters Patent No. 632,927, dated September 12, 1899.

Application filed December 3, 1897. Renewed August 4, 1899. Serial No. 726,207. (No model.)

To all whom it may concern:

Be it known that I, JAMES T. ROBERTS, a citizen of the United States, residing at Anderson, in the county of Anderson and State 5 of South Carolina, have invented a new and useful Fabric-Tufting Machine, of which the following is a specification.

This invention relates to tufting-machines of the class which are operated by hand and 10 comprise similar parts having sliding connection and disposed so as to have a reciprocating movement when in operation, one of the parts or members carrying a needle and the other a holder or check to prevent the 15 withdrawal of the thread after the loop has been formed.

The purpose of the present invention is to provide a joint between the parts or sections 20 of the machine which will direct them in their reciprocating movements and prevent their separation when in operation and which will admit of the movement being regulated so as to vary the length of loop according to the thickness of the goods or pile being operated 25 upon.

For a full understanding of the merits and advantages of the invention reference is to be had to the accompanying drawings and the following description.

30 The improvement is susceptible of various changes in the form, proportion, and the minor details of construction without departing from the principle or sacrificing any of the advantages thereof, and to a full disclosure 35 of the invention an adaptation thereof is shown in the accompanying drawings, in which—

Figure 1 is an elevation of a tufting-machine constructed in accordance with this invention, one of the parts or sections being broken away, disclosing the rib and slot joint. Fig. 2 is a perspective view of the machine, the parts being separated and showing the means for varying the relative reciprocating 45 movement. Fig. 3 is a transverse section showing the joint composed of two ribs and corresponding slots therefor.

Corresponding and like parts are referred to in the following description and indicated 50 in the several views of the drawings by the same reference characters.

The machine is composed of similar parts,

halves, or sections 1, which are placed with their inner edges together and are expanded at their rear ends, forming grips for convenience and ease of handling when in operation, the front ends of the parts being contracted to present a pleasing and graceful appearance. One of the parts or sections has a longitudinal slot 2, which is undercut at its front 55 end and is provided with a recess 3 at its rear end. The other part is formed with or has applied thereto a rib 4, which is inclined at its front end to enter the undercut end of the slot 2 and is formed with a rear extension 5 60 to enter the recess 3 and prevent a separation of the sections or parts 1 when at the limit of their rearward movement. The rib 4 has a longitudinal slot 6 and a pin 7 passing transversely through the slot 2, and the slot 6 holds the parts 1 together at all times. When the part provided with the rib 4 is at the limit of its forward movement, the inclined or beveled end of the rib interlocks 70 with the undercut end of the slot 2 and prevents any outward displacement of the parts 75 and relieves the pin 7 in a great measure of any strain tending to separate the parts.

The needle 8 may be applied to either one of the parts and, as shown, has adjustable connection with the part carrying the rib 4, which will be designated as the "needle-section" part or half. By having the needle adjustably connected with the machine the length of the loop may be regulated according to 85 the thickness of the fabric, goods, or cloth to be tufted. The loop-holder 9 is fitted to the opposite or checking section in such a manner as to be shifted in accordance with the position of the needle with which it co-operates. 90

In order to vary the reciprocating movements of the parts, the rib 4 has a series of openings 10, in any one of which is adapted to be fitted a pin 11, the latter extending across the slot 6 and the path of the pin 7, so 95 as to engage with the latter and limit the sliding movements, as set forth. The number of ribs 4 and slots 2 is immaterial, and, as shown in Fig. 3, two ribs and a corresponding number of slots are provided, the construction being otherwise the same in every respect.

It is proposed to make the machine in different sizes and of material varying in nature, kind, and quality, according to the finish

and character of machine, and in some instances the machine will be manufactured solely of wood and in others of metal or a combination of metal and wood, and when 5 completed the machine may be plain or ornamented, as desired.

Having thus described the invention, what is claimed as new is--

1. In a fabric-tufting implement, the members or parts slidably related, one member having the longitudinal groove, 2, at its inner edge with the undercut terminals, a projecting rib, 4, fast with the inner edge of the other member and having the prolonged ends 15 arranged to fit the undercut terminals of the groove, 2, the length of said rib being less than the groove and the width of the rib corresponding nearly to the depth of the groove to guide the members in their slidable movement and house the rib entirely within the 20 grooved member, and stop devices to limit the strain of the members or parts, whereby the prolonged ends of the rib are adapted to

enter the undercut ends of the groove at the limit of the movement of the members in 25 either direction, substantially as described.

2. In a fabric-tufting machine, the combination of parts slidably related, one of the parts having a longitudinal slot and the other formed with a longitudinally-slotted rib to 30 enter and reciprocate in the aforesaid longitudinal slot, a pin passing transversely through the slotted part and the slot of the rib, and another pin adapted to enter one of a series of openings in the rib and engage with the 35 first-mentioned pin and limit the relative sliding movements of the parts, substantially as set forth.

In testimony that I claim the foregoing as my own I have hereto affixed my signature in 40 the presence of two witnesses.

JAS. T. ROBERTS.
